UNITED STATES PATENT OFFICE.

WILLIAM F. RICHEY AND THOMAS DALY, OF PARIS, TEXAS; SAID RICHEY ASSIGNOR TO SAID DALY.

LIQUID-FUEL BURNER.

SPECIFICATION forming part of Letters Patent No. 785,271, dated March 21, 1905.

Application filed March 18, 1904. Serial No. 198,758.

To all whom it may concern:

Be it known that we, WILLIAM F. RICHEY and THOMAS DALY, citizens of the United States, and residents of Paris, in the county of Lamar and State of Texas, have invented a new and Improved Liquid-Fuel Burner, of which the following is a full, clear, and exact description.

Our invention relates to apparatus for burning liquid fuel.

10 The objects of our invention are to provide a device for burning oil and other liquid fuel which shall atomize the fuel before reaching the burner and elevate the temperature of the fuel, so as not only to thoroughly mix it with 15 steam, but to actually effect a chemical combination of the two, resulting in a highly-inflammable gas which when injected into the furnace atmosphere and lighted burns with a pure white flame entirely without smoke and 20 without a particle of carbon deposit. Air, however, may be used instead of steam.

Reference is to be had to the accompanying drawings, forming a part of this specification, in which similar characters of reference indicate corresponding parts in all the figures.

Figure 1 is a longitudinal sectional view of one form of our invention. Fig. 2 is a plan view of the same with the top part removed. Fig. 3 is a fragmentary perspective view of a 30 detail, and Fig. 4 is a perspective view of an attachment hereinafter more particularly described.

In the drawings, 1 represents a fitting carrying the pipe for the admission of liquid fuel. 35 2 is a chambered connection fitted to the part 1 and carrying a steam-admission pipe, and 3 is a union screw-threaded into the connection 2 and provided with a ground-joint for permitting the parts to be swung through 40 a complete circle upon it.

4 is a nut attachment for securing the parts together and which is intended to be loosened when the parts are to be separated.

5 is a double-ended coupling connecting the 45 described parts with the mixing-chamber, which is represented by 6. Upon the upper end of the mixing-chamber is secured a cap 7 by means of bolts 7^a. This cap is provided with a convex baffle-surface 7^b. Between the

parts 6 and 7 is secured a baffle-plate 8, provided with projections 8^a and slots 8^b.

9 is an outlet-pipe from the chamber 6, which pipe is provided with a nozzle 10, having a slot 10^a.

An opening in the upper part of the nozzle 55 is closed by a screw-threaded plug or cap 10^b, which can be manipulated by applying a wrench to the squared upper part. Adjustment of the size of the slot 10^a can thus be obtained, so that the area thereof can be made 60 of greater area than the oil-tube itself or can be reduced to any fineness desired. Evidently no possible trouble from choking can occur, and any desired amount of fuel can be delivered to the furnace promptly and in proper 65 form. Furthermore, this nozzle-opening is in most (perhaps all) burners the point that suffers most from frictional wear, and renewals are in most cases quite frequent and troublesome. This trouble is eliminated altogether 70 in this nozzle, for a very slight movement of the cap will close the gate, and the wear of the point is immediately taken up. The nozzle is sectional and is always easy of access when in operation. It is adjustable, has unlimited 75 range of work, is simple in construction, and we might say "wearproof." Speed, reliability, economy, and simplicity, with a capacity of burning any liquid fuel to be had at short notice—all of these qualities we claim 80 for our burner.

The lower part of the cap above the slot is curved, thus permitting the stream of mixed steam and oil to turn the easy curve with a tendency to sweep by the slot to the hollow 85 of the curved bend 10, forming an eddy with a tendency to fall back in a shower. It is then caught by the outflowing stream and delivered to the furnace in proper shape for instantaneous ignition. The upper part of the 90 nozzle projects upwardly at 10°. Instead of this nozzle the nozzle 10^d, provided with a convex upwardly-extending surface 10^e, with crossed slots 10^f, as shown in Fig. 4, may be attached to the outlet-pipe 9. This attachment 10^d is to be used for upward projection 95 in the production of a vertical flame and may have any number of slots, such as those

shown, according to the amount of fuel to be consumed.

11 is a steam-pipe attached to the coupling 5 and extending through the lower wall of 5 the chamber 6 and well up into the chamber beyond the baffle-plate 8.

12 is a fuel-pipe secured in the fitting 1 and passing through the steam-passage about half-way up to the pipe 11. This fuel-pipe 12 is 10 provided at the top with a cap 13, having a valve-seat. The cap 13 is large enough to almost fill the steam or air tube at the point where the oil is first brought into company or contact with steam, thus giving it a sort 15 of nozzle velocity at the critical point and moment. Again, at this very point the fuel is also delivered in a thin circular stream and meets the path of the inflowing steam at the neutral angle of forty-five degrees. The 20 lower and upper parts 14^a and 14^b of the valve 14 are coned to the same angle, so that the flow of the two streams—oil and steam—will meet with no appreciable resistance and from now on will travel together more or 25 less crowded, striking the first baffle-plate already partly mixed. The oil now reduced to a hot foam from its situation in the presence of live steam suddenly expands into a highly-attenuated oily film having but little 30 more consistency than the steam itself, and from now on the tendency of both fuel and steam is to follow the regular law of gases and vapor mixtures, each taking full possession of the entire space just as if either were 35 not present, and the pressure in the chamber is not that due to the steam or oil pressure alone; but most likely it is equal to the sum of both the individual pressures. The result 40 of this is fully demonstrated in the clear transparent flame of dazzling brightness that always accompanies a proper handling of the valves. These propositions are not mere theoretical expectations, but actual facts from 45 practical observations.

45 The valve 14 has a packing 15 and a hand-screw 16.

17 is a drip-cock provided in the wall of the chamber 2.

By virtue of the construction of this device 50 the oil or other liquid fuel passing up the pipe 12 through the narrow opening formed by the valve 14 and valve-seat in the cap 13 into the steam-pipe 11 will mix there with the steam, and both will strike the baffle-surface 55 face 7^b with considerable force. This will cause the mixture to be dispersed and forced backwardly through the slots in the baffle-plate 8, causing further dispersion of the two fluids. The mixed and combined fluids will 60 then be forced out through the slots 10^a or 10^f, as the case may be, in the form of a fine spray of high inflammability, and the spray will be burned at this point with the accompanying evolution of great heat.

65 Although we have spoken of "oil" and

"steam" throughout, this has been for convenience only, as any fluid fuel may be used and many other mediums than steam may be advantageously employed. Air preferably under an elevated temperature and pressure 70 would operate in all essential respects in the manner described, and we do not wish to limit our invention to the fluids mentioned.

Having described our invention, we claim as new and desire to secure by Letters Patent— 75

1. A liquid-fuel burner comprising a chamber having a tube for admitting steam entering it near one end of the chamber, a liquid-fuel inlet within said tube, means for mixing the fluid and fuel comprising a tortuous passage surrounding said tube, and having an outlet near the end of the chamber at which said tube enters the chamber. 80

2. A liquid-fuel burner, comprising a chamber having a liquid-fuel inlet, a steam-inlet, 85 and means for intimately mixing the steam and fuel, said last-mentioned means comprising a surface opposite said fuel-inlet, and an apertured plate within said chamber out of the direct path of the fuel from the inlet to 90 said surface.

3. A liquid-fuel burner, comprising a chamber having a liquid-fuel inlet, a steam-inlet, means for regulating the admission of fuel, 95 and means for intimately mixing the steam and fuel, said last-mentioned means comprising a convex surface and a plate having corrugations on one surface and surrounding said inlets.

4. A liquid-fuel burner comprising a chamber 100 having a fluid-inlet, a regulatable liquid-fuel inlet within said fluid-inlet, a baffle-plate opposite said fluid-inlet at one end of the chamber, and an outlet at the other end of the chamber comprising a nozzle provided 105 with an independently-adjustable slit.

5. A liquid-fuel burner, comprising a chamber having a liquid-fluid inlet, an inlet for vaporizing fluid, and means for intimately mixing the fluid and fuel, comprising a convex surface closing the end of said chamber opposite said inlets, and a mixing-plate within said chamber; said chamber having an outlet near the end opposite said convex surface, and a pipe leading from said outlet and provided with a nozzle. 110

6. The combination of a liquid-fuel pipe, a steam-pipe, a connection attached to both of said pipes and having a steam-chamber, a mixing-chamber, connections from said steam-chamber to said mixing-chamber, comprising an adjustable nut, a tube extending from said connections into the interior of the mixing-chamber, a tube extending from said fuel-pipe into said connections toward said mixing-chamber, and a baffle-plate in the mixing-chamber and surrounding said first-mentioned tube. 120

7. A liquid-fuel burner comprising a chamber having a liquid-fuel inlet, a steam-inlet, and means for intimately mixing the steam 125 and fuel.

and fuel, comprising a convex surface opposite said inlets, and a slotted plate surrounding said inlets.

8. A liquid-fuel burner comprising a chamber having a liquid-fuel inlet, a steam-inlet, and means for intimately mixing the steam and fuel, comprising a convex surface closing the end of said chamber opposite said inlets, and a slotted plate within said chamber and adjacent to said inlets, said chamber having an outlet near the end opposite said convex sur-

face, and a pipe leading from said outlet and provided with a nozzle having an adjustable slot.

In testimony whereof we have signed our names to this specification in the presence of two subscribing witnesses.
